UNITED STATES PATENT OFFICE.

HENRY BREHMER, OF STAPLETON, ASSIGNOR TO DAVID WOLFE BRUCE, OF NEW YORK, N. Y.

DESIGN FOR TYPE.

SPECIFICATION forming part of Design No. 15,748, dated January 27, 1885.

Application filed December 13, 1884. Term of patent 14 years.

To all whom it may concern.

Be it known that I, HENRY BREHMER, (assignor to DAVID WOLFE BRUCE,) of Stapleton, county of Richmond, and State of New York, 5 have invented a new Design for a Font of Printing-Type, of which the following is a specification.

The nature of my design is clearly shown in the accompanying typographic impression, 10 to which reference is made; and it consists of a letter the face of which is ornamented to give it the appearance of chased workmanship. The right-hand up and down portions of the A, K, and R are extended below the line, and 15 ornamented at base by a curved line extending to the left and terminating in the dot. The left-hand up and down portions of the H, M, and N are extended below the line, and or-

namented at base by a curved line extending to the right and terminating in the dot. The up and down portions of the symbol "and" are extended below the line, and ornamented by a light curved line, with dot termination extending to the left.

The character of the design is preserved in 25 the punctuation-marks, numerals, and dollar and pound-sterling marks, so far as the ornamentation of the face is concerned.

I claim as new—

The design for a font of printing-type, as 30 shown and described.

HENRY BREHMER.

W. V. H. HICKS,
